Specification for Design.

Patented Oct. 29, 1918.

Application filed May 6, 1918. Serial No. 232,954. Term of patent 7 years.

To all whom it may concern:

Be it known that I, HERMAN A. QUADE, a citizen of the United States, residing at Milwaukee, in the county of Milwaukee and State of Wisconsin, have invented a new, original, and ornamental Design for Wall-Paper Moisteners, of which the following is a specification, reference being had to the accompanying drawing, forming part thereof.

In the drawings—

I claim:

The ornamental design for a wall paper moistener, as shown.

In testimony that I claim the foregoing I have hereunto set my hand at Milwaukee, in the county of Milwaukee and State of Wisconsin.

HERMAN A. QUADE.
